UNITED STATES PATENT OFFICE.

GEORGE S. THOMPSON, OF HOPKINTON, MASSACHUSETTS, AND CHARLES F. RICHARDSON, OF WOONSOCKET, RHODE ISLAND, ASSIGNEES TO THOMPSON ENGINE STARTER COMPANY, OF NEW YORK, N. Y., A CORPORATION OF NEW YORK.

ENGINE-STARTER.

1,186,955.

Specification of Letters Patent. Patented June 13, 1916.

Application filed May 23, 1913. Serial No. 769,372.

To all whom it may concern:

Be it known that we, GEORGE S. THOMPSON and CHARLES F. RICHARDSON, citizens of the United States, residing at Hopkinton, county 5 of Middlesex, Massachusetts, and Woonsocket, county of Providence, Rhode Island, respectively, have invented certain new and useful Improvements in Engine-Starters, of which the following is a full, clear, and 10 exact description.

The invention which constitutes the subject matter of this application relates to an automatic means for starting an engine, and while the embodiment of the invention here- 15 in described and illustrated in the accompanying drawings is especially designed for cranking the engine of an automobile, it will be obvious that the invention in its broadest aspect is not confined to this specific use.

Referring to the drawings which show the preferred embodiment of our invention, Figure 1 is a view in perspective to show more or less diagrammatically one convenient way of mounting the starter. Fig. 2 is an en- 20 larged cross-sectional view of starter mechanism. Fig. 3 is a longitudinal section on line 3—3 of Fig. 2. Fig. 4 is a cross-section on line 4—4 of Fig. 3. Figs. 5 and 6 are details on an enlarged scale.

The character 10 designates a suitable housing in which the starting mechanism is confined and operates. The starting mechanism is mounted upon the engine supports 11 and located at one side of the engine 12, 25 just under the bonnet, not shown, thus giving ready access to the various parts of the starter when desired. Preferably fixed upon the engine shaft 13 is a sprocket gear 14 over which a sprocket chain 15 of the silent 30 type is adapted to operate the latter in turn connected to a gear 16 loosely encircling a rotatable power shaft 17 which is suitably journaled in the housing 10. Mechanism operatively connected to the gear 16 is pro- 35 vided for automatically cranking the engine and also mechanism for restoring, in turn, power in the spring. We will now proceed to describe in detail these respective means for cranking the engine and restoring 40 power in the power spring. Located in proximity to the gear 16 and rotating around the power shaft 17 in unison therewith, is another gear 18. This gear 18 is riveted or otherwise secured to gear 16 and

so far as the cranking of the engine is concerned, it performs no particular function, but is necessary in the restoration of power in the power spring. The gear 16 carries a plurality of spring pressed plungers or pawls 19 which are located in sockets 20, as 55 clearly shown in Fig. 3. The pawls are provided with ears 21 that slide in grooves 22 of said gear which prevents rotation of the plungers relative to the said gear. The gear 18 is provided with annular perforations 23 through which the rearward ends of said 60 plungers project. Located in the forward end of each of the sockets 20 is a suitable spring 24 which tends to urge the pawl rearwardly. This rearward movement of the 65 pawl is limited by the fact that one end of the ear 21 comes into contact with the forward side of gear 18, it being understood 70 that the pawl is so shaped at its rearward end as to effect a snug fit with the perforations in said gear 18.

Located upon the power shaft 17 and fixed to rotate therewith is a clutch member 25 which is capable of longitudinal movement with respect to this shaft. This member is 80 provided with laterally projecting ratchet teeth 26 which are adapted to be engaged with and disengaged from the pawls 19, protruding through gear 18, when the said member is moved longitudinally upon said power shaft. Loosely mounted upon the shaft is a worm wheel 27 provided with laterally projecting teeth 28 which are adapted to normally engage corresponding sockets 29 in the clutch member, 85 the said teeth and sockets effecting an interlocking engagement between the said worm gear and the said clutch member, said engagement being maintained until one of said elements is moved relative to the other. The 90 rear end of the power shaft is connected to a power spring 30. For the sake of convenience, the part 31 of the shaft to which the spring is connected may be disconnectible from the main power shaft at the point 32. 95

The clutch member is provided with a circumferential flange 33 adapted to be constantly engaged by a forked member 34 having a groove 35 on the interior thereof which corresponds in shape to the shape of the circumferential flange. This forked member is fixed preferably to a shaft 36 which is adapted to be moved longitudinally by 100

means of a lever 37 pivoted at 38 upon the housing 10. A spring 39 is employed to hold the upper ends of this lever in its forward position which in turn holds the clutch member in interlocking engagement with the worm wheel 27 as clearly illustrated in Fig. 3. To the upper end of the lever 37 is connected a wire rope or cord 40 extending through the dash board of the machine and there connected to suitable mechanism for effecting a rearward pull upon the lever 37. When the spring is wound up let it be assumed that certain instrumentalities are connected with the worm wheel 27, for holding the same stationary, and inasmuch as the clutch member is fixed to the power shaft and is in interlocking engagement with the worm wheel, obviously no unwinding can take place, and the operation in cranking the engine is as follows: When the lever 37 is pulled to its rearward position, it disengages the clutch member from the worm wheel, but before it is completely disengaged therefrom the lateral teeth 26 on the clutch member are beginning to engage with the spring pressed pawls 19. Consequently when the clutch member 25 is completely disengaged from worm wheel 27 it is in effective operative engagement with gears 16-18 and the power spring now acts, through the power shaft and clutch member, to rotate the gears 16-18 to crank the engine, the power spring and gears 14 and 16 being so constructed as to impart about eight revolutions to the crank shaft in the operation of cranking the engine. During the cranking of the engine the teeth on the clutch member 25 are held in engagement with the pawls 19 by the turning force of the latter or by continued tension on lever 37. But as soon as the engine is cranked the pawls, owing to their peculiar formation, run "ahead" of the teeth on the clutch member, thus permitting the latter to be retrieved, by means of the spring 38 connected to lever 37, the tension on lever 37 being removed, into interlocking engagement with worm wheel 27. Those parts that have not been previously described are now in position to effect a rewinding of the power spring. Having described the mechanism and the operation thereof, for cranking the engine, we will now proceed to describe the mechanism associated with the aforesaid mechanism for the restoration of energy in the power spring. Suitably journaled in the casing and movable longitudinally with respect to the same is a counter shaft 42 upon which is loosely located a gear 43 which meshes with gear 18 and which is provided with laterally and rearwardly projecting teeth 44, similar to teeth 28 on worm wheel 29. Around that part of the shaft rearwardly from the gear 43 is a sleeve 45, the said shaft adapted to move longitudinally with

respect to this sleeve independently of the movement of the latter, but is fixed to rotate in unison therewith. Upon the sleeve 45 and movable longitudinally with respect to the same is a second clutch member 46 provided with sockets 47 which are adapted to receive the teeth 44 of gear 43, and which are similar to the sockets 29 in the clutch member 25. The sleeve 45 is slotted as indicated at 48 to receive a pin 49 which extends through the counter shaft and so connects the said shaft and the said clutch member 46 that any longitudinal movement imparted to the former will be likewise imparted to the latter. The clutch member is rotatably fixed to sleeve 45 by means of a key 77 and said clutch member is slideable longitudinally on the said key. Owing to the slot 48 in sleeve 45 a longitudinal movement may be imparted to the shaft and clutch member without necessarily being imparted to the said sleeve. Fixed to the sleeve 45 is a spiral gear 50 which meshes with another spiral gear 51 fixed on a vertical shaft 52 having suitable bearings 53 and 54. To this vertical shaft 52 is also secured a worm gear 55 which meshes with worm wheel 27. Let it be assumed therefore that the device is provided with certain instrumentalities for moving the counter shaft longitudinally and forwardly to cause an interlocking engagement between the gear 43 and the clutch member 46 and also that the spring is unwound and the engine cranked; the process of restoring energy in the spring is as follows: As before stated, as soon as the engine is cranked the clutch member 25 is released from the pawls 19 of gears 16-18 and the said clutch member is moved rearwardly by means of the spring 39 connected to lever 37 and interlocks with worm wheel 27 and establishes again a rigid connection between the latter and the power shaft to which the power spring is connected. The gear 43 being in mesh with gear 18, which is now being rotated by means of sprocket chain 15 and sprocket gear 14, will impart to sleeve 45, to which the spiral gear 50 is fixed, a rotative movement through the interlocking engagement of the said gear 43 and clutch member 46. This rotative movement of spiral gear 50 is in turn transmitted to the worm wheel 27 through spiral gear 51, shaft 52 and worm gear 55, the latter meshing with the said worm wheel 27. The rotation of worm wheel 27 imparts in turn a rotative movement to the power shaft by reason of the interlocking engagement between the said worm gear and member 27 and this rotation of the power shaft, which, as will be obviously understood, is in the opposite direction to its rotation in cranking the engine, restores energy in the power spring.

The mechanism for moving the counter

shaft longitudinally to effect an interlocking engagement between gear 43 and clutch member 46 to restore energy in the power spring and to effect a disengagement of said gear and member after the spring is wound up, we will now proceed to describe in detail. Fixed to the power shaft and within the housing 10 is a gear 56 which meshes with a gear 57 provided with a pinion 58, which gear and pinion are mounted upon a common shaft 59. The pinion in turn meshes with a gear 60 located upon a shaft 61. Projecting laterally from one side of this gear 60 is a stud or other member 62 which is adapted to contact with the opposite sides of a lug on arm 63 projecting at right angles to the axis of rotation of said shaft. The outer end of this arm 63 is pivoted to a link 64 which is in turn pivoted to an arm 65 keyed to the shaft 66. The latter has another arm 67 projecting at an angle to the aforesaid arm, said arm 67 being provided with a stud 68 projecting at right angles therefrom and adapted to engage between the flanges 69 which constitute a sort of neck. When the clutch 46 moves into and out of mesh with the teeth on gear 43, positive power is required to maintain the parts in their proper relative position. In case the spring "dies" out too soon, it is possible that stud 62 located on gear 60 may not revolve far enough around to lift lever 63 up, thereby not pushing clutch 46 into mesh with teeth 44. The link 64 is therefore continued up through casing 10 and is provided with a pin 78 to enable the operator to pull up on said link 64, whereby the parts may be placed in proper position for effecting a rewinding of the spring. The tension of the spring motor is controlled by the stud 62 and when "wound up" said stud contacts with the opposite side of the arm 63 pushing the latter together with the link 64 downwardly thereby disengaging the clutch 46 from gear 43.

To supplement the action of the mechanism just described, we employ a segment 70 fixed to shaft 66 in mesh with a gear 71 located upon stud 72 projecting from the supporting arm 73. The gear 71 is provided with an arm 74 to which is connected a spring 75 the opposite end of the spring being suitably connected at a fixed point 76. In the position shown in Fig. 3, the shaft 42 is in its rearmost position and is so maintained by virtue of the spring 75 being on one side of a dead center. When the stud 62 contacts with arm 63 the counter shaft 42 will be moved inwardly as will be understood and the spring will be thrown on the opposite side of the dead center. This action of the spring therefore not only supplements the throw of the shaft but effectively maintains the shaft in its extreme positions. The sprocket gears 16-18

loosely mounted upon the power shaft and the sprocket gear 14 fixed to the crank shaft are operated by the spring actuated means to crank the engine and in turn operate the spring actuated means to store up energy in the spring. As soon as the sprocket gears 16-18 are released from operative engagement with the spring actuated mechanism, after energy has been stored in the power spring, it will be necessary to hold the said spring actuated mechanism against operation. This we accomplish by the arrangement of the spiral gear and the worm gear on the vertical shaft 52, as it will be understood motion can be imparted to the worm wheel 27 only by the rotation of the worm gear in mesh therewith. It will also be apparent that the pressure from the worm wheel upon the worm gear acts upon the threads of the latter at substantially right angles to the direction of the same. Consequently there can be but little, if any, rotative movement acting upon the worm gear. If there be a rotative moment it is so slight that its effect is *nil*. It will therefore be seen that we have eliminated the extraneous or the independent holding mechanism which is invariably used in engine starters. The worm wheel and gear have therefore a dual function, namely, to hold the spring actuated mechanism against rotation and to coöperate with other mechanism to store up energy in the power spring. This not only reduces the number of parts to a minimum, but also insures a better operation of the starter.

From the above description, it will be observed that after the engine is cranked and energy restored in the power spring the only parts that operate, so long as the engine continues to run, is the sprocket gears 14, 16-18, gear 43 and the sprocket chain 15, and as these parts are out of engagement with the other parts of the starter there can be no wear outside of that which occurs during the brief interval of time required to crank the engine and restore energy in the power spring. The housing which incloses the mechanism is preferably made fluid tight so that the various parts may be run in oil, if so desired. It will be sufficient, however, if the fixed sprocket gear 14 and chain 15 are run in oil. This will necessarily lubricate the other parts of the starter and thus reduce the wear to a minimum.

The invention comprises another important feature, viz., that in cranking the engine the number of rotations of the crank shaft corresponds substantially to the number of revolutions of the power shaft; while in restoring energy in the power spring the number of revolutions of the power shaft is considerably less than the number of revolutions of the engine shaft. In fact it will be obvious that the ratio of the number of

revolutions of the engine shaft to the power shaft in cranking the engine and in restoring energy in the power spring may be varied indefinitely according to the particular requirements.

It is to be understood that we do not limit ourselves to the particular embodiment which we have chosen to illustrate our invention, as it is perfectly obvious, in the light of the foregoing description taken in connection with the constructions herein shown, that various other modifications may be resorted to and minor changes made without necessarily departing from the true spirit and scope of the invention.

What we claim is:—

1. In an engine starter, an engine shaft, in combination with starting mechanism for operating said shaft and mounted independently thereof, said mechanism comprising a power shaft, a sprocket gear rotatably mounted upon said shaft, means for operatively connecting said sprocket gear and engine shaft, a clutch member rotatably fixed to said power shaft but capable of longitudinal movement thereon, said sprocket gear and clutch member provided with means for effecting an interlocking engagement between the same as one is moved toward the other, means normally engaging said clutch member to hold the latter stationary, and mechanism for moving said clutch member out of engagement with the last mentioned means and into clutching engagement with the sprocket gear to crank the engine.

2. In an engine starter, an engine shaft, a power shaft, a sprocket gear rotatably mounted upon said power shaft, and means for operatively connecting the sprocket gear and engine shaft, in combination with means for rotating said sprocket gear to crank the engine, said means comprising a clutch member rotatably fixed to said shaft but capable of longitudinal movement thereon, means normally engaging said clutch member to hold the same stationary, and means for moving the clutch member longitudinally of said power shaft out of engagement with the last mentioned means into clutching engagement with the sprocket gear whereby the shaft is permitted to rotate the said clutch member and sprocket gear to crank the engine.

3. In an engine starter, an engine shaft, a power shaft, a sprocket gear loosely mounted upon said power shaft, and means for operatively connecting the sprocket gear and engine shaft; in combination with means for rotating said sprocket gear to crank the engine, said means comprising a clutch member rotatably fixed to said shaft but capable of longitudinal movement thereon, means normally engaging said clutch member to hold the same stationary, and means for

moving the clutch member longitudinally of said shaft to release the same from said engaging means and to bring the same into clutching engagement with the sprocket gear, said clutching engagement being established before the clutch member is released from its holding means, substantially as described.

4. In an engine starter, an engine shaft, a power shaft, and means for operatively connecting the sprocket gear and engine shaft; in combination with means for rotating said sprocket gear to crank the engine, said means comprising a clutch member rotatably fixed to said power shaft but capable of longitudinal movement thereon, means normally engaging said clutch mechanism to hold the same stationary, means for moving the clutch member longitudinally of said shaft to release the same from said engaging means and to bring the same into clutching engagement with the sprocket gear for rotating the latter to crank the engine, and means for automatically moving the clutch member in the opposite direction after a certain number of rotations of said sprocket gear to disengage the same from the sprocket gear and to cause the same to reengage the aforesaid holding means.

5. In an engine starter, an engine shaft, a power shaft, a sprocket gear on said power shaft, and means for operatively connecting the sprocket gear and engine shaft; means for rotating said sprocket gear to crank the engine, said means comprising a clutch member rotatably fixed to said power shaft but capable of longitudinal movement thereon, means normally engaging said clutch mechanism to hold the same stationary, means for moving the clutch member longitudinally of said shaft to release the same from said engaging means and to bring the same into clutching engagement with the sprocket gear to rotate the latter to crank the engine, and means for automatically returning the clutch member to normal position, in combination with means connected to and operated by said sprocket gear after the engine is cranked for rotating said clutch member to restore energy to the power spring.

6. In an engine starter, an engine shaft, a power shaft provided with a power spring, a sprocket gear rotatably mounted upon said power shaft, and operatively connected to the engine shaft, a clutch gear rotatably fixed to said power shaft but capable of longitudinal movement thereon, rotatable means normally engaging said clutch mechanism to hold the same stationary, means for moving the latter out of engagement with said rotatable means into clutching engagement with said sprocket gear to crank the engine, means for automatically returning the clutch member to normal position in engagement with said rotatable holding

means, and means operatively connected to said sprocket gear for rotating said rotatable holding means and said clutch member for restoring energy in the power spring.

- 5 7. In a starting apparatus for explosive engines, in combination, an engine shaft, a gear fixed to said shaft, a power shaft operated by power means, a sprocket gear loosely mounted upon said power shaft, 70 means on said power shaft operated in one direction by the power means to rotate the sprocket gear to crank the engine, and mechanism connected to said sprocket gear for operating the aforesaid means in the opposite direction to store up energy in the power means, said mechanism comprising means for holding the aforesaid means normally stationary against the tension of said power means. 75
- 10 8. In a starting apparatus for explosive engines, an engine shaft, a power shaft, a sprocket gear mounted on said shaft, and means for operatively connecting the sprocket gear and engine shaft; in combination with means actuated by said sprocket gear after the engine has been cranked to restore power in the power means, comprising a gear rotatably mounted upon the power shaft, a clutch member fixed to said shaft 80 and normally in interlocking engagement with the last mentioned gear, and mechanism operatively connecting the sprocket gear and the last mentioned gear. 85
- 15 9. In starting apparatus for explosive engines, an engine shaft, a power shaft, a sprocket gear loosely mounted upon said power shaft, and means for operatively connecting the sprocket gear and engine shaft; in combination with means operatively connected to said sprocket gear and actuated by the engine after the latter has been cranked to restore power in the power means, comprising a gear wheel rotatably mounted upon the power shaft, a clutch member fixed to 90 said shaft and in interlocking engagement with the last mentioned gear, a counter shaft located adjacent said power shaft, a toothed gear loosely mounted thereon and operatively connected to the sprocket gear, and means for effecting an operative connection between said toothed gear and the said gear wheel. 95
- 20 10. In a starting apparatus for explosive engines, an engine shaft, a power shaft, a sprocket gear loosely mounted upon said power shaft, means for clutching the sprocket gear to the power shaft, and means for operatively connecting the sprocket gear and engine shaft; in combination with means operatively connected to said sprocket gear and actuated by the engine after the latter has been cranked to restore power in the power means, comprising a gear wheel rotatably mounted upon the power shaft, 100 a clutch member fixed to said shaft and nor-
- 25 mally in interlocking engagement with the last mentioned gear, a counter shaft located parallel and adjacent to said power shaft, a toothed gear rotatably mounted upon said counter shaft and operatively connected to the aforesaid sprocket gear, a clutch member normally out of engagement with said toothed gear, means for operatively connecting the said clutch member with the aforesaid gear wheel, and means for effecting an interlocking engagement between the clutch member and toothed gear whereby the rotation of the latter will be imparted to the clutch member and to the gear wheel. 105
- 30 11. In a starting apparatus for explosive engines, an engine shaft, a fixed gear thereon in combination with power means operatively connected to said fixed gear for cranking the engine, and mechanism associated with the aforesaid means after the engine has been cranked and actuated by the said engine to restore power in power means; said cranking means comprising a power shaft, a sprocket gear rotatably mounted upon said power shaft, and means adapted to 110 engage with and rotate said sprocket gear to crank the engine; and said restoring mechanism comprising a gear wheel rotatably mounted upon the power shaft and normally in engagement with the last mentioned means, a counter shaft arranged adjacent to said power shaft, a toothed gear rotatably mounted thereon and operatively connected to said sprocket gear, and means operatively connecting said toothed gear and said gear wheel whereby the latter and the said means in normal engagement therewith are rotated by the former to restore energy in the power means. 115
- 35 12. In a starting apparatus for explosive engines, an engine shaft, a fixed gear therein, and cranking means operatively connected to said fixed gear comprising a spring actuated power shaft, a sprocket gear rotatably mounted upon said power shaft, and means adapted to engage with and rotate said sprocket gear to crank the engine, in combination with mechanism operated in turn by the engine for restoring energy in the spring after the engine has been cranked, comprising a gear wheel rotatably mounted upon the power shaft and normally in engagement with the last mentioned means, a counter shaft arranged adjacent to said power shaft, a toothed gear rotatably mounted thereon and operatively connected to said sprocket gear, and means operatively connecting said toothed gear and said gear wheel whereby the latter and the said means in normal engagement therewith are rotated by the former to restore energy in the power means. 120
- 40 13. In a starting apparatus for explosive engines, an engine shaft, a fixed gear thereon, cranking means operatively connected to 125

said fixed gear comprising a spring actuated power shaft, a sprocket gear rotatably mounted upon said power shaft, and a normally stationary member slidably mounted 5 upon and rotatably fixed to said power shaft adapted to be brought into engagement with and to rotate said sprocket gear to crank the engine, in combination with mechanism operated in turn by the engine for restoring 10 energy in the spring after the engine has been cranked, comprising a counter shaft arranged adjacent to said power shaft, a toothed gear rotatably mounted thereon and operatively connected to said sprocket gear, 15 and means operatively connecting said toothed gear and said normally stationary member whereby the latter is rotated by the former to store energy in the power means.

14. In a starting apparatus for explosive 20 engines, an engine shaft, a fixed gear thereon, cranking means operatively connected to said fixed gear, comprising a spring actuated power shaft, a sprocket gear rotatably mounted upon said power shaft, and a normally 25 stationary member adapted to be brought into operative engagement with the sprocket gear and operated in one direction by the spring actuated power shaft to crank the engine, in combination with means 30 adapted to operatively connect said normally stationary member and actuated by the sprocket gear after the engine has been cranked to operate the said member in the other direction to store up energy in the 35 power spring.

15. In a starting apparatus for explosive 40 engines, an engine shaft, a fixed gear thereon, cranking means operatively connected to said fixed gear comprising a spring actuated power shaft, a sprocket gear rotatably mounted upon said power shaft, and a normally 45 stationary member adapted to be brought into operative engagement with the sprocket gear and operated in one direction by the spring actuated power shaft to crank the engine, and means for automatically 50 disengaging the normally stationary member from the sprocket gear, in combination with means operated by the sprocket gear and 55 connected to said member for rotating the latter in the opposite direction to store up energy in the power spring, and means for automatically connecting and disconnecting the aforesaid means from the sprocket gear at the beginning and the end respectively of the restoring operation.

16. In a starting apparatus for explosive 60 engines, an engine shaft, a fixed gear thereon, cranking means operatively connected to said fixed gear comprising a spring actuated power shaft, a sprocket gear rotatably mounted upon said power shaft, and a normally 65 stationary member adapted to be brought into operative engagement with the

sprocket gear and operated in one direction 65 by the spring actuated power shaft to crank the engine, in combination with means to store up energy in the spring, comprising a counter shaft arranged adjacent to the power shaft, a toothed gear rotatably 70 mounted thereon and operatively connected to the sprocket gear, means actuated by the said toothed gear for rotating the normally stationary member in the opposite direction to restore energy in the spring, and means 75 for automatically connecting and disconnecting the aforesaid means with the toothed gear at the beginning and end respectively of the restoring operation.

17. In a starting apparatus for explosive 80 engines, an engine shaft, a fixed gear thereon, cranking means operatively connected to said fixed gear comprising a spring actuated power shaft, a sprocket gear rotatably mounted upon said power shaft, a clutch member fixed to said shaft but longitudinally movable thereon, rotatable means on said shaft normally in interlocking engagement with said clutch member, means for normally holding the aforesaid means 85 against rotation, and means for moving the clutch member out of interlocking engagement with said rotatable means into clutching engagement with the sprocket gear whereby the same is actuated by the power 90 shaft to rotate the sprocket gear to crank the engine, in combination with means to store up energy in the spring comprising a toothed gear rotatably mounted adjacent to the power shaft and actuated by the sprocket 95 gear, and a clutch member operatively connected to the holding mechanism and adapted to be brought into clutching engagement with the toothed gear to rotate the holding mechanism and the first mentioned clutch 100 member in the opposite direction to store up energy in the power spring.

18. In a starting apparatus for explosive 110 engines, an engine shaft, a fixed gear thereon, cranking means operatively connected to said fixed gear comprising a spring actuated power shaft, a sprocket gear rotatably mounted upon said shaft, a clutch member fixed to said shaft but longitudinally 115 movable thereon, rotatable means on said shaft normally in interlocking engagement with said clutch member, means for normally holding the aforesaid means against rotation, and means for moving the clutch member out of interlocking engagement with said rotatable means into clutching 120 engagement with the sprocket gear whereby the same is actuated by the power shaft to rotate the sprocket gear to crank the engine.

19. In a starting apparatus for explosive 125 engines, an engine shaft, a fixed gear thereon, a sprocket gear rotatably mounted ad-

jacent and operatively connected to said engine shaft, spring actuated power means adapted to engage with said sprocket gear and actuated in one direction to rotate the 5 same, to crank the engine, and means connecting said sprocket gear to the power means and operated by said sprocket gear after the engine has been cranked for actuating the power means in the opposite direction to restore energy in the power means, said connecting means normally serving to hold the spring actuated means against rotation.

20. In a starting apparatus for explosive engines, an engine shaft, a fixed gear thereon, a sprocket gear rotatably mounted adjacent and operatively connected to said fixed gear, in combination with spring actuated means for engaging with the sprocket 20 gear and rotated in one direction to crank the engine, and means actuated by the engine after the same has been cranked to restore energy in the power spring, comprising mechanism connected to the sprocket 25 means to rotate the same in the opposite direction, said mechanism adapted to hold the spring actuated means normally stationary against the tension of the power spring.

21. In a starting apparatus for explosive engines, an engine shaft, a fixed gear thereon, a sprocket gear rotatably mounted adjacent and operatively connected to said first gear, spring actuated means adapted to operatively engage with the sprocket gear and 35 rotate in one direction to crank the engine, in combination with mechanism operated by the sprocket gear after the engine has been cranked to rotate the spring actuated means in the opposite direction to restore energy 40 in the power spring, said restoring mechanism normally engaging with the spring actuated means to hold the same stationary against the tension of the power spring.

22. In a starting apparatus for explosive engines, an engine shaft, a fixed gear thereon, a power shaft located adjacent to said engine shaft, a counter shaft located in proximity to the power shaft, a sprocket gear rotatably mounted upon the power 50 shaft and operatively connected to the fixed gear on the engine shaft, a toothed gear rotatably mounted upon the counter shaft and operatively connected to the sprocket gear, spring actuated means adapted to engage with the sprocket gear and to be rotated in one direction to crank the engine, and mechanism adapted to engage with the spring actuated means and operated by the toothed gear to rotate the spring actuated 55 means in the other direction to restore energy in the power spring.

23. In a starting apparatus for explosive engines, an engine shaft, a fixed gear thereon, a power shaft located adjacent to said

engine shaft, a counter shaft located in 65 proximity to the power shaft, a sprocket gear rotatably mounted upon the power shaft and operatively connected to the fixed gear on the engine shaft, a toothed gear rotatably mounted upon the counter shaft and 70 operatively connected to the sprocket gear, means engageable with the sprocket gear and rotated in one direction by the power means to crank the engine, and means operable by the toothed gear and engageable 75 by the aforesaid means for rotating the latter in the opposite direction to store up energy in the power means.

24. In a starting apparatus for explosive engines, an engine shaft, a fixed gear thereon, a power shaft located adjacent to said engine shaft, a counter shaft located in proximity to the power shaft, a sprocket gear rotatably mounted upon the power shaft and operatively connected to the fixed 80 gear on the engine shaft, a toothed gear rotatably mounted upon the counter shaft and operatively connected to the sprocket gear, means engageable with the sprocket gear and rotated in one direction by the power 85 means to crank the engine, and mechanism operable by the toothed gear and engageable by the aforesaid means for rotating the latter in the opposite direction to store up energy in the power spring, in combination 90 with means actuated by the power mechanism for bringing the said mechanism into operative engagement with said toothed gear when the engine is cranked and for disengaging the same after energy has been 100 restored in the power spring.

25. In a starting apparatus for explosive engines, an engine shaft, a fixed gear thereon, a sprocket gear rotatably mounted adjacent and operatively connected to said fixed 105 gear, spring actuated means adapted to operatively engage with the sprocket gear and rotated in one direction to crank the engine, and mechanism operated by the sprocket gear after the engine has been cranked to 110 rotate the spring actuated means in the opposite direction to restore energy in the power spring, in combination with means actuated by the power means for bringing the said mechanism into operative relation 115 with said sprocket gear when the engine is cranked and for disconnecting the same after energy has been restored in the power spring.

26. In a starting apparatus for explosive 120 engines, an engine shaft, a fixed gear thereon, a sprocket gear rotatably mounted adjacent and operatively connected to said fixed gear, spring actuated means adapted to operatively engage with the sprocket gear and 125 rotate in one direction to crank the engine, in combination with mechanism operated by the sprocket gear after the engine has been

cranked to rotate the spring actuated means in the opposite direction to restore energy in the power spring.

27. In a starting apparatus for explosive engines, an engine shaft, a gear operatively connected to said shaft, in combination with spring-actuated power means operatively connected to said gear to actuate the latter to crank the engines, and mechanism associated with said power means and actuated by the engine after the same has been cranked for restoring energy in the power

means, said mechanism comprising means serving to hold the power means, after energy has been restored therein, against the tension of the power spring.

In testimony whereof we affix our signatures in the presence of two subscribing witnesses.

GEORGE S. THOMPSON.
CHARLES F. RICHARDSON.
